UNITED STATES PATENT OFFICE

119,152

DESIGN FOR A SAMPLE FABRIC DISPLAY CARD

Sydney E. Bender, Brooklyn, N. Y.

Application December 9, 1939, Serial No. 88,781

Term of patent 3½ years

To all whom it may concern:

Be it known that I, Sydney E. Bender, a citizen of the United States, residing at Brooklyn, in the county of Kings and State of New York, have invented a new, original, and ornamental Design for a Sample Fabric Display Card, of which the following is a specification, reference being had to the accompanying drawing, forming part thereof.

I claim:

The ornamental design for a sample fabric display card, as shown.

SYDNEY E. BENDER.
